UNITED STATES PATENT OFFICE.

CHARLES H. QUARLES, OF CHARLOTTESVILLE, VIRGINIA, ASSIGNOR, BY MESNE ASSIGNMENTS, TO AMERICAN AUTOMATIC TRAIN CONTROL CORPORATION, A CORPORATION OF MARYLAND.

SUPPORT FOR CONTACT-SHOES.

1,391,502.

Specification of Letters Patent. Patented Sept. 20, 1921.

Application filed November 17, 1919. Serial No. 338,645.

To all whom it may concern:

Be it known that CHARLES H. QUARLES, a citizen of the United States, residing at Charlottesville, in the county of Albemarle 5 and State of Virginia, has invented certain new and useful Improvements in Supports for Contact-Shoes, of which the following is a specification.

This invention relates to an improved support for contact shoes of train-stop and control mechanism.

The object of the invention is to provide an improved construction of shoe-support whereby in case the same or any material 15 part thereof becomes loose or broken to an extent as to cause a failure in its operation, an automatic operation of other mechanisms will result that will disclose the defective condition.

20 In the operation of train control mechanisms of the ramp rail type, a contact shoe is carried on the vehicle in such position as to successively engage and be operated by the ramp rails located along the trackway 25 and it quite frequently happens that the supports or brackets which carry the shoe plunger become loose or broken and allow the shoe to assume a position where it will fail to engage the ramp rails. This failure 30 to make contact will cause the shoe to give a false clear signal or indication which obviously is dangerous and the present invention is designed to meet and overcome this serious defect.

35 The invention is illustrated in the accompanying drawing, wherein,—

Figure 1. illustrates a vertical sectional view through the base, the cylinder and the lower end of the plunger.

40 Fig. 2. shows a plan view of the base and the end supporting-brackets.

Fig. 3. illustrates the head-part of the support in bottom view, and

Fig. 4. shows a top view of the cylinder.

45 Referring to the drawing, the numerals 5, designate two spaced-apart brackets which are bolted to the frame of the vehicle and each has a horizontal ledge 6, which extends outwardly from the vehicle.

50 A base plate 7, has a horizontal flange 8, at its opposite edges which are seated on the bracket ledges and each of said base-plate flanges is provided with vertical threaded perforations 9, for the passage of adjusting

55 screws 10, which latter project through the flanges and seat on top of the bracket-ledges 6, and are utilized merely for slight adjusting purposes.

The flanges 8, are also provided with vertical perforations 11, which register with 60 similar perforations 12, in the bracket-ledges so that locking-bolts 13, may be passed vertically through the two registering perforations to rigidly lock the base 65 down on the ledges.

The base plate also has a central circular opening 14, and is further provided with a plurality of perforations 15, adjacent to said central opening which perforations extend through downwardly-projecting bosses 70 16, on the bottom side of the base.

By reference to the sectional view of the base, shown in Fig. 1, of the drawing, it will be noted that the metal of the base is quite thick and that the flanges 8, thereof 75 are provided with horizontal passage portions 17 and 18, which open at the vertical side edges 19 and 20 of the flanges. These passage-portions 17 and 18, as shown best in Fig. 2, of the drawing, are not directly 80 opposite in the base flanges but are preferably located one (18) nearer the front and the other (17) nearer the rear. The relative location of these passage portions, and the number of the same, is not essential to 85 the invention, and may differ from that shown, but the outer ends of the passages terminate in enlarged recesses 21, which latter are internally screw-threaded.

Confronting each of the recesses 21, and 90 the ends of the passages 17 and 18, are vertical flanges 22, which extend upwardly from the bracket-ledges 6. Each flange 22, has a horizontal perforation 23, therethrough which registers with, but is of a larger diameter than, the recesses 21, so that a screw plug 24, may be passed through the perforation and screwed into the threaded recess. Each screw-plug has a head 25, at its outer 95 end and also has a central passage 26, therein which communicates with the passage-portions 17 or 18, as the case may be. These central passages 26, in the screw-plugs however do not extend through the latter but are simply blind passages, and terminate in the 100 heads 25, at the outer side of the flanges 22.

The inner ends of the passage portions 17 and 18, in this instance, incline upwardly at

27, and communicate with a passage 29, that extends horizontally around the base plate and all the way around the central opening 14, so that said passage 29 and both lateral passages 17 and 18 are always in communication.

10 It will be noted that the passage 29 extends through the base plate in a horizontal plane between the upper and lower surfaces thereof and that it has a stretch along the front, another stretch along the rear and the two stretches extend from and connect the front and rear stretches.

15 At one side of the central opening 14, the base plate also has a short branch passage 30, which extends laterally from one of the front-to-rear stretches of the passage 29, and that the inner end of this branch passage 30, connects with a vertical passage 31, that 20 opens in a circular recess 32, on the top side of the base plate. The purpose of this circular recess will presently be explained.

25 The base plate sustains a vertical cylinder 33, which latter is provided with an annular flange 34 around its upper edge that seats on a gasket 35 on the top of the base, and around the central opening 14. The vertical cylinder depends through the central opening 14, and its lower end terminates beneath 30 the bottom of the base.

35 On the interior, the cylinder 33, has a chamber 36, with an annular flange or shoulder 37, at its lower end and an opening 38, in said lower end adjacent to said shoulder.

40 A packing ring 39, is seated on the shoulder 37, around the opening 38, in the lower end of the chamber, for a purpose that will presently be explained.

45 At the upper end, the cylinder 33, has an annular recess 40, and at one side the annular flange 34, of said cylinder has a vertical opening or slot 41, which is positioned directly over the circular recess 32, on the top of the base-plate, and said flange also has a plurality of vertical openings or perforations 42, which register with the perforations 15, that extend down through the bosses 16, on the base plate, all for a purpose that will presently be explained.

50 On top of the cylinder flange there is provided a head-part 43, that has an interior central chamber 44, which registers with the chamber 36 in the cylinder beneath it, and the bottom of this head has a central annular bead that enters the top recess 40, of the cylinder flange and seats on a packing ring 45, in said recess.

55 The head part 43, is provided at one side with a depending bottom lug 46, that projects down through the slot or opening 41 in the cylinder flange and enters the circular recess 32, in the top of the base plate. A packing disk 47, is located in the recess 32, and makes a tight joint about the lower 60 end of the lug 46, so that a passage way 48,

may be provided that extends down through the head-part; through the lug 46, and an opening in the packing disk 47, and communicates with the vertical passage 31, in the base-plate. This latter passage-way 31, 70 opens into the branch passage 30, all for a purpose that will presently be explained.

75 The upper end of the passage 48, communicates with an air-supply passage 50, which extends from the outer side, through the head-part and opens into the central chamber 44. This air-supply passage 50, is connected to the main air-supply of an air-brake mechanism on the vehicle so that at all times said passage 50, will be charged 80 with air from the air-brake system and will be subject to variations in the air-pressure just the same as is the main air or train-line pipe of the air-brake system.

85 As passage 50, is always in communication with the air-supply of the air-brake main or train line, and said passage is always in communication with chambers 44, and 36, said latter chambers will also be constantly charged with air-pressure equal 90 to the pressure in the train-line.

95 The gaskets or packings 45 and 47, prevent leakage of air from the passages and chambers to the atmosphere and the cylinder, head and base parts are all drawn 100 closely together by means of bolts 51, which extend vertically through those parts by passing through the perforations 15 and bosses 16; perforations 42, and screwing into threaded sockets or perforations 52, in the head-part 43.

105 The perforations 15, that extend down through the bosses 16, of the base are preferably lined with insulated bushings 53, and insulating washers 54, are also provided between the heads of the bolts 51, and the bottom-ends of the bosses.

110 A plunger rod 55, extends vertically through the cylinder chamber 36, and chamber 44, of the head-part, and said rod carries a piston 56, which snugly fits the chamber 36, but which is electrically insulated from the rod by means of insulation 57. The plunger-rod 55, passes through a stuffing-box 58, at the upper side of the head-part and insulating material 59, is provided to electrically insulate the rod from the head-part.

115 The lower end of the plunger rod 55, carries a contact head 60, which is designed to 120 make frictional contact with ramp rails along the roadway and pick up current from said rails when the latter are energized. This feature in the operation has nothing to do with the present invention and is therefore not shown herein.

125 A passage 61, extends vertically in the plunger rod and terminates at or adjacent to the contact head 60.

130 This passage is entirely closed at the

lower end but at its upper end has a lateral branch 62, that opens at the side of the rod so as to communicate with the chamber 44, and allow air under pressure to enter said 5 passage from the chamber. This passage 61 and branch 62, is not a feature of the present invention and therefore is not herein claimed.

A spring 63, encircles the rod and is confined in the chambers 36 and 44, and serves to press the piston head 56, and rod 55, down, but will yield to allow the rod to move upwardly when the contact head 60, engages a ramp rail.

15 From the foregoing explanation it will be noted that the air-supply passage 50, is in communication with the chambers 44 and 36, and constantly supplies air under pressure from the air-brake train line to said 20 chambers and also to the branch passage 62 and central passage 61, in the plunger-rod. It will also be seen that said air-supply passage 50 also communicates through passages 48 and 31, to the branch passage 30, and 25 from the latter to the passage 29 around the base; the lateral passages 17-18; the recesses 21 and the plug-passages 26, so that all of the passages through the base and the passages 26 in the screw plugs 25, are constantly charged with air under pressure that 30 is in continuous communication with the train line of the air-brake system.

The object of providing these blind passages through the base plate of the shoe support and into the plug caps 25, is to so distribute those passages through the supporting structures as to provide for the leakage or escape of air in case a crack or break occurs in any of the parts that might cause a 40 failure in the operation of the plunger-rod. If such crack or break should occur, it would extend through some portion of one or more of the blind passages and when it does occur, will permit the air to escape to the atmosphere and produce an automatic operation of the air-brakes, by automatically venting the train line pressure, substantially as would occur if the engineer manually actuated his engineer's valve to produce such venting of the train line.

50 Thus by means of this novel arrangement of blind passages in the shoe-supporting structure, a break of sufficient magnitude as to cause a failure of the shoe to operate, 55 would automatically produce an operation of the air-brakes because of the leakage of air through such ruptured part.

It will also be noted that should the securing bolts 51, become loose there would be 60 a leakage of air around the packings 40 or 47, and such leak would reduce the train line pressure and cause an application of the air-brakes.

Having described my invention, I claim,—
65 1. In a contact shoe for railway vehicles

the combination with a cylinder, of a contact plunger projecting from the cylinder and having a passage toward but is closed adjacent to the contact end thereof said plunger-passage being always in communication with the cylinder; a base for supporting said cylinder said base having air-passages extending therein which are closed against atmospheric communication but which communicate with the said cylinder 75 and a connection from the train line of an air-brake system to said base passages which connection is constantly maintained.

2. In a contact shoe for railway vehicles the combination with a cylinder, of a contact plunger extending through the cylinder and having a passage therein which opens into the cylinder; a base for supporting the cylinder said base having air passages that extend therein around the cylinder which 80 passages are closed against atmospheric communication but are in communication with the cylinder and a connection for supplying air from the train line of an air-brake system on the vehicle to said passages 85 and cylinder.

3. In a contact shoe for railway vehicles the combination with a base having air-passages therein which are closed against atmospheric communication, of a cylinder 95 sustained by said base; a contact plunger passing through the cylinder and having a passage extending downwardly therein whose lower end is closed but which passage communicates with the cylinder said cylinder 100 and the base-passages being in communication and a connection for supplying air under pressure to said passages and cylinder.

4. In a contact shoe for railway vehicles the combination with supporting brackets, 105 of a base sustained by said brackets; fastening devices engaging the base and brackets,—the base having air passages with ends that are closed by the fastening devices; a connection for supplying air from the train 110 line of an air-brake system on the vehicle to said base passages, and a movable contact element carried by the base.

5. In a contact shoe for railway vehicles the combination with supporting brackets, 115 of a base sustained by said brackets and having air passages therein; a cylinder sustained by the base and having a chamber that is in communication with the base-passages; a plunger movable in the cylinder 120 and having a passage that communicates with said cylinder-chamber; fastening means engaging the base and sealing the air-passages in the base and a connection for supplying air from the train line of an air-brake system on the vehicle to said passages and chamber-cylinder.

In testimony whereof I affix my signature.

CHARLES H. QUARLES.
